Atty's:

UNITED STATES PATENT OFFICE.

JOSEPH M. BATES, OF ATTLEBOROUGH, MASSACHUSETTS.

BRACELET.

SPECIFICATION forming part of Letters Patent No. 269,166, dated December 19, 1882.

Application filed May 8, 1882. (No model.)

To all whom it may concern:

Be it known that I, JOSEPH M. BATES, of Attleborough, in the county of Bristol and States of Massachusetts, have invented a new and useful Improvement in Bracelets; and I hereby declare that the following is a full, clear, and exact description of the same, reference being had to the accompanying drawings, forming part of this specification.

10 The better quality of bracelets are usually made either entirely of precious metal or of what is known in the art as "stock-plate"—that is to say, of inferior metal, usually brass, plated with precious metal, usually gold, and drawn or rolled down to the thickness required. The hinge of such bracelets is usually made of inferior metal and provided with the sleeve for the pivot, either of precious metal or of stock-plate. A stop is also required to limit the 15 opening of the bracelet, and this invention has reference to an improved construction of the hinge provided with the stop-pieces; and it consists in securing a strip of either precious metal or stock-plate to the two sides of the hinge-plate and drawing or rolling the same into the proper section, as will be more fully set forth hereinafter.

20 Figure 1 is a perspective view of my improved hinge, showing the lines of a bracelet in connection therewith in broken lines. Fig. 2 is a section of the stock as drawn or rolled before the stop is secured. Fig. 3 is a section showing the fine metal bar for forming the stop, secured. Fig. 4 is a section showing the hinge-plate after it has been drawn out and is ready to receive the tubular wire for the hinge. Fig. 5 is an end view of the hinge, showing its 25 relation to the bracelet, which is indicated in broken lines.

25 In the drawings, *a* is the drawn or rolled piece of inferior metal forming one of the plates or wings of the hinge when completed. It has the recess *b*, into which the bar *d* is secured by solder. This bar is made of precious metal, or of inferior metal plated with precious metal, and, when secured, the whole is drawn or rolled into the shape shown in Fig. 4. The

tubular wire, forming the sleeve for the hinge, is now secured into the concave *c*, and the wings are shaped to fit the interior of the arms 50 of the bracelet where they are secured. The hinge-pin is now inserted and the two wings are united thereby. All the metal in sight is now of the same quality as the bracelet, and the stops form an ornamental rib across the 55 same—one on each side of the hinge. By this construction, time, labor, and precious metal are saved.

The stops *d d* form a reliable guide for securing the wings of the hinge in the bracelet, 60 the whole forming a strong hinge and a durable connection with the wings of the bracelet, covering the joint, as the stops extend over the width of the wings, as shown in Fig. 1.

I am aware that stops have heretofore been 65 applied to hinges of various descriptions to limit the movement of the hinged members on their pivot, and I therefore do not wish to claim such a device, broadly.

Having thus described my invention, I claim 70 as new and desire to secure by Letters Patent—

1. A hinge for a bracelet consisting of the two wings *a a*, constructed to enter the bracelet, each provided with the stop *d* and the sleeve *e*, as described.

2. The improved method of constructing the 75 hinges of bracelets, the same consisting in drawing or rolling a piece of inferior metal to nearly the shape of the wings, securing a bar of precious metal or stock-plate to the inferior metal, then drawing or rolling the whole into the desired form, so that the bar secured will form the stop *d*, when the bracelet is completed, as described.

3. A hinge for a bracelet consisting of the 80 wings *a a*, made of inferior metal, having the stops *d d* and the sleeves *e e*, secured thereto so as to present the precious metal only to view when the bracelet is completed, as described.

J. M. BATES.
